ATTORNEY

UNITED STATES PATENT OFFICE.

FLORENCE A. THORNTON, OF CORSICANA, TEXAS.

SANITARY UDDER-PROTECTOR.

1,311,728.

Specification of Letters Patent. Patented July 29, 1919.

Application filed March 20, 1918. Serial No. 223,604.

To all whom it may concern:

Be it known that I, FLORENCE A. THORNTON, a citizen of the United States, residing at Corsicana, in the county of Navarro and 5 State of Texas, have invented certain new and useful Improvements in Sanitary Udder-Protectors, of which the following is a specification.

This invention relates to improvements in 10 dairy appliances and more particularly to udder protectors.

The object of the invention is to provide a simply constructed and efficient sanitary udder protector for milch cows to prevent 15 contact of the udder with foreign matter and to keep it warm, thereby enhancing the comfort of the animal and improving the quality of the milk.

With the foregoing and other objects in 20 view, which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

In the accompanying drawing is represented 30 a perspective view of the protector constituting this invention.

In the embodiment illustrated, an udder sack 1 is shown of a size to fit the udder of a cow and constructed of thin flexible 15 rubber to render it moisture proof and to adapt it to snugly fit the udder, also to permit it to expand as the udder fills. This sack 1 has teat pockets 2 depending from its bottom and positioned to receive the cow's 0 teats.

This sack is adapted to be secured in operative position by means of a harness composed of side straps 3 connected by stitching or otherwise to the sack at its diametrically 5 opposite sides, bracing straps 4 being also connected with the sack and to the side straps. The side straps 3 are made of a length sufficient to extend up over the back of the cow and are provided with separable 10 fasteners for detachably connecting the free ends thereof, a buckle 5 being here shown which preferably has a pad 5' arranged thereunder to protect the cow's back against chafing.

Secured to the rear of the bag or sack 1

between the side straps 3 are hip straps 6, which are spaced from each other and from the side straps and are adapted to extend between the hind legs of the cow and to diverge, one passing over one hip of the cow 60 and the other over the other hip and connected respectively to the side straps 3, preferably by buckles 7 or other detachable fastening means. When these straps are so positioned and connected, the udder will be 65 completely inclosed by the sack, the free edges of which contact with the body of the cow in such manner that nothing can touch the udder.

The straps 3 and 6 have arranged therein 70 longitudinally yieldable inserts 8 which are preferably composed of strong flexible rubber, and which are designed to yield to permit the free movements of the cow when feeding.

This improved protector which is designed to be worn while the animal is in the stall or grazing in a field may be left in place at all times except during the milking of the animal, and it is of course understood that the 80 sack or bag 1 will be made in different sizes to fit different sized udders. The straps 3 and 6 or the major portions thereof are preferably constructed of webbing, but not necessarily so, and by having the yieldable 85 inserts 8 therein the movements of the cow will be accommodated, and hence the udder protector will not be uncomfortable or in any way interfere with the animal's ordinary movements. 90

From the foregoing description, taken in connection with the accompanying drawing, the advantages of the construction and of the method of operation will be readily apparent to those skilled in the art to which 95 the invention appertains and while I have described the device which I now consider to be the best embodiment thereof, I desire to have it understood that the device shown is merely illustrative and that such changes 100 may be made as are within the scope of the claimed invention.

I claim:

In a device of the class described, a sack composed of thin flexible rubber shaped to 105 encompass and snugly fit the udder of a cow and having integral teat pockets, side straps secured to the upper edge of said sack at diametrically opposite points, bracing straps connected at one end with said sack on oppo- 110

site sides of said side straps at points spaced therefrom and connected at their other ends to said side straps, rear straps secured at one end to the sack between the side straps at 5 points spaced from each other and from the straps and detachably connected at their other ends to the side straps near the upper ends thereof, and longitudinally yieldable inserts

arranged intermediately of the ends of both the side and rear straps.

In testimony whereof I affix my signature in presence of two witnesses.

FLORENCE A. THORNTON.
